VACUUM CLEANING MACHINE

Rollen G. Leonard, Indianapolis, Ind., assignor to
 Continental Car-Na-Var Corporation, Brazil,
 Ind., a corporation of Indiana

Application June 16, 1948, Serial No. 33,361

12 Claims. (Cl. 183—13)

1

This invention relates to a vacuum cleaner particularly of the heavy duty type which will provide a vacuum chamber into which is drawn dirt and refuse to be separated from the air before reaching the operating motor by reason of the stream of air which carries the dirt being carried through a water bath.

While the invention is particularly adapted to heavy duty work, it is of course capable of being produced in various sizes for different types of work.

A primary object of the invention is to provide a structure which will be not only very effective in producing a relatively high degree of vacuum, but will also carry picked up dirt and foreign matter through a quantity of water to separate that matter from the air flow before reaching the vacuum producing motor, and without permitting any part of that water, even in vapor form, to reach the motor.

A further primary object of the invention is to provide a structure of the nature indicated which will permit the removal of the separated dirt simply by manipulating a valve to cause the dirt to be forced out into any convenient receptacle or the like apart from the machine, all without having to clean any separate dust bag or other chamber requiring removal from the device itself.

A still further important object of the invention is to provide a structure wherein the operating motor will operate in a continuous manner in one direction and by means of some type of a valve cause a vacuum to be produced in the intake chamber, and when desired, to create a pressure in that chamber in order to force out the dirt laden water and sediment which may have collected therein, all without having to change the motor drive in any respect.

These and many other objects including the simplicity of construction permitting easy access to the various members of the device, and the easy manipulating of the entire structure, will be understood by those versed in the art in the following description of one particular form of the device as illustrated in the accompanying drawings, in which

Fig. 1 is a view in top plan of a structure embodying the device and also in partial section at various transverse levels from the top of the device;

Fig. 2, a detail in vertical section on the line 2—2 in Fig. 1;

Fig. 3, a diametrical vertical section on the line 3—3 in Fig. 1;

2

Fig. 4, a transverse section on the line 4—4 in Fig. 3;

Fig. 5, a detail in vertical section on the line 5—5 in Fig. 1;

Fig. 6, a detail in outside vertical elevation of the end of an operating valve;

Fig. 7, a detail in vertical elevation through the upper portion of the device on the line 7—7 in Fig. 1; and

Fig. 8, a detail in vertical section on the line 8—8, in Fig. 1.

Referring to the drawings in which like characters of reference indicate like parts throughout the several views, a cylindrical container 10 hereinafter termed a tank is provided. This tank 10 may be provided with any suitable support desired such as a separate cart, or casters applied directly thereto, the cart and casters not being shown since they do not form a part of the invention per se. The upper end of the tank 10 is closed off by a pair of nested pans, a major pan 11, and an inner pan 12, supported in spaced apart relation to provide an annular compartment 13 therearound, extending under the floor

14 of the tank 12 which is spaced a distance above the floor 15 of the pan 11. The pan 12 has a horizontally disposed annular flange 16, the outer portion of which rests directly upon the top side of the flange 17 extending horizontally and annularly from the pan 11. These two flanges 16 and 17 are held compressively one against the other by means of an annularly grooved resilient gasket 18 receiving those flanges therein, this gasket 18 being provided with a major portion 19 extending under the flange 17, and then continuing therefrom around and over on top of the flange 16 by a portion 20. The diameters of the flanges 16 and 17, and consequently of the gasket 18 are such that the gasket will be disposed over the top edge 21 of the tank 10.

A dome 22 is formed to have an under surface 23 to rest upon the top portion 20 of the gasket 18, and to have a downturned flange 24 extending vertically downwardly on the outside of that gasket 18. Thumb screws 25, Figs. 6 and 1, are hinged by transverse pins 26 carried through ears 27 fixed to the tank 10, to be rockable around to vertically disposed positions to enter within slots 28 provided in the lugs 29 extending radially beyond the dome 22. Then on the upper ends of these screws 25 there is a wing nut 30 by means of which the dome 22 may be pulled down compressively against the gasket 18 so as to form a seal between the dome, the flanges 16 and 17, and the top edge 21 of the tank 10. In the form

40

45

50

55

herein shown, there are three of these thumb screws 25 employed to effect the desired seal.

From the inner, underside of the dome 22 there extends downwardly an annular wall 31 which terminates by an inturned, horizontally disposed annular flange 32. Against the underside of this flange 32 there is compressed a resilient gasket 33 by means of a retaining ring 34, through which a plurality of screws 35 are carried to screw-threadedly engage with the flange 32. This gasket 33 extends radially inwardly toward the center of curvature of the flange 32 a distance sufficient to permit resting upon its top side, the flange 36 turned horizontally and outwardly from a motor containing can 37. This can 37 is carried by the gasket 33 by means of screws 38 passing down through the flange 36 and into an under securing ring 39 located against the underside of the gasket 33. The annular edge of the flange 36 and also of the retaining ring 39 are each respectively spaced from the flange 32 to permit vertical travel within a limited degree of the can 37.

Within the can 37 is mounted a motor 40 to have its armature disposed about a vertical axis 41. The motor 40 may be mounted within the can in any number of different ways, and is herein shown as being supported, through a ring 42 having the ears 43 resting on brackets 44 extending inwardly of the can 37, and the ears secured in position by means of screws 45, Fig. 1. The commutator 46 is herein shown, Fig. 3, as being disposed above the top level of the can 37. On the lower end of the armature shaft is secured in driving relation a vacuum producing fan or turbine wheel 47, Fig. 3, and the can floor 48 is provided with a central opening 49 therethrough, located centrally of the wheel or fan 47. The direction of rotation of the motor armature is such that the fan 47 will pull air into the can 37 through the opening 49, and discharge that air upwardly out of the top side of the can 37, across the motor itself, and also outside of the ring 42, between it and the flange 36.

In view of the description of the structure so far set out, there is formed between the dome 22, the can 37, and the inner pan 12 and its extending flange 16, a chamber generally designated by the numeral 50. Also there is defined another chamber 51 between the top of the dome 22 and the top of the can 37 and its flange 36. The chamber 51 is sealed off from the chamber 50 by means of the gasket 33. At all times, the chamber 50 constitutes a chamber within which there is at least a partial vacuum while the motor 40 is running, and at the same time, the chamber 51 is under pressure. These two conditions never change throughout the entire operation of the device.

The floor 15 of the pan 11 is provided with an opening 53 therethrough, and this opening has its margin covered by a resilient grommet 54, Fig. 7. Then there is a filter chamber 55 formed to fit between the walls of the pans 11 and 12 to have its underside centered over this opening 53, and the chamber to extend around between the two pan walls 11 and 12 a substantially equal circumferential distance, Fig. 1. The ends of this chamber 55 are provided with perforations 56, as indicated in Fig. 5, and the chamber itself is normally provided with a filling of any suitable air filtering medium such as wool or cotton waste 57, or the like. Spun glass, spun metal, or any of such filter materials may be employed.

Within the chamber 55 there is provided a dome 58 made out of a foraminous material, such

as metal screen wire, Fig. 7. This dome 58 is provided to withhold the fibrous material 57 from dropping through the opening 53. The chamber 55 is fitted snugly between the two pans 11 and 12 so that the only exit of air therefrom as may be pulled into that chamber through the opening 53 is through the end walls designated respectively by the numerals 59 and 60.

From the floor 15, externally of the pan 11 there extends downwardly a nipple 61, the upper end portion of which surrounds the opening 53. The lower end of this nipple 61 is left open, and a valve of some sort, herein shown as a flexible ball 62 is carried within that nipple 61, and retained therein in its lower position by any suitable means, such as by the cross-wire 63. This valve member 62 is provided to be raised by floating upon water upwardly to fit snugly against the grommet 54, and provide a seal against that grommet so as to prevent an undue height of water within the tank 10 from entering into the chamber 55.

The vertical depth of the pan 11 is such that it occupies only a minor portion of the vertical height of the upper end of the tank 10, as best indicated in Fig. 3. Below the floor 15 of the pan 11 there is provided an intake pipe 64 which is detachably connected inside of the tank to a nipple 65 which is fixed to the tank wall to extend outwardly therefrom, the outer end of this nipple 65 being used as a means to which any suitable hose (not shown) may be attached to extend to the ordinary cleaning nozzle. The pipe 64 extends horizontally inwardly of the tank 10 from its connection with the nipple 65 for a distance herein shown as past the axis of the tank 10, and then turns downwardly by a vertical length 66 to open into a cap 67 which is supported over a drum 68, in turn resting on the floor 69 of the tank 10.

The drum 68 is essentially a cylindrical vessel open at its top end, and having a floor 70 over approximately half of its area, Fig. 3. This floor 70 is spaced upwardly a distance from the floor 69 of the tank 10. The opening 71 through the floor 70 of the drum 68 is on a side of the drum 68 opposite to that side toward which the vertical portion 66 of the pipe 64 is directed. The under side of the cap 67 is open entirely across its lower end, and from the cylindrical wall 72 of this cap 67 there extends horizontally outwardly an annular flange 73 sufficient to extend to at least and as herein shown, slightly beyond the vertical wall 74 of the drum 68. The cap 67 is spaced above the top edge of the wall 74 to leave an annular opening 75 therebetween, this opening 75 being between the top edge of the wall 74 and the underside of the flange 73. This opening 75 is fixed in vertical height, and is so proportioned that when air may be drawn downwardly from the pipe 64 into the cap 67, some of the air may escape through this opening 75, while the major portion will be required to travel downwardly through the opening 71 and thence up into the inside of the tank 10. Normally the tank 10 is supplied with water up to a level indicated by the line 76, Fig. 3. The water level may vary somewhat, primarily above that line 76, but never below the opening elevation 75.

A valve of any suitable construction, is employed to selectively interconnect the chambers 13, 50, and 51 whereby a desired flow of air is obtained through the tank 10 and the nipple 65. For example when the device is to be operated to pull air into the nipple 65 and into the tank 10

in the normal cleaning operation, the valve employed is set to cause the fan wheel 47 to evacuate the chambers 13 and 50 to discharge through the can 37 into the chamber 51, and from there into the atmosphere. Then in a subsequent action to eliminate the accumulated dirt from the tank 10, the valve employed is changed to a second position whereby the chamber 51 is interconnected with the tank 10 so as to apply pressure thereto and force the flow initially of water containing the dirt outwardly through the pipe 64 and the nipple 65, while air is introduced from the atmosphere into the chambers 50 and 13. That is the air introduced into the two chambers 13 and 50 is taken upwardly through the can 37 to supply the pressure in the chamber 51.

As indicated, the valve employed may be of a construction varying considerably. Therefore one particular form of the valve is herein illustrated only to show one possibility of the valving arrangement.

In this form, there is disposed horizontally across the dome 22 a cylindrical valve housing 77 within which is disposed a valve core 78 which may be rocked on its horizontal axis by means of an externally disposed lever 79. The valve housing 77 has a port 79a through its underside opening into a down turned nipple 80. This port 79a is adjacent that end of the housing toward which the handle 79 is mounted. The nipple 80 has a ferrule 81 frictionally retained in its lower end portion to extend downwardly through the flange 16 into the chamber 13 between the pans 11 and 12, Fig. 2. Between the lower end of the nipple 80 and the top face of the flange 16 there is disposed a resilient gasket 82 so that an air seal is effected between the nipple and the flange 16 when the dome is drawn down toward the top end of the can 10 as above described. The gasket 82 surrounds the ferrule 81 and is therefore very effective as a seal not only between the lower end of the nipple 80 and the top face of the flange 16, but also prevents escape of air between the nipple 80 and the flange 16 between the ferrule 81 and the inner wall of the nipple 80. The lower end of the ferrule 81 projects into the chamber 13 a distance, and this lower end of the nipple is surrounded by a wire mesh cup 83 which is fixed by its upper edge portion to the under side of the flange 16. The nipple 80 is located substantially diametrically across the dome 22 from the opening 53 through the floor 15 of the pan 11, Fig. 1.

Adjacent the port 79a, is a second port 84 through the underside of the valve housing 77. This port 84 opens into the chamber 50 which, as above indicated, is a vacuum chamber. Then there is a third port 85 spaced longitudinally along the underside of the housing 77 also opening into this chamber 50.

Now referring to the valve core 78, this core is shown in the various views in that position wherein the device is operating in the normal manner to pull air into the nipple 65 and into the tank 10. The valve core 78 has a reduced diameter hub 86 on the right hand end as viewed in Fig. 2, and fixed on this hub 86 is the operating lever 79. This lever 79 is fixed thereto by any suitable means, herein shown as by a pin 87 carried through the lever 79 and the hub 86. To prevent longitudinal travel of the valve core 78 relative to the housing 77, the lever 79 is provided with a hub 88 and around that hub there is formed an annular groove 89 into which the end of a screw 90 is entered. Also to hold the valve core 78 in the position for normal operation as above

indicated, there is employed a torsion spring 91 having an end portion 92 entering the valve core 78, Fig. 2, from which the spring 91 coils around the hub 86 and then terminates by an end 93 extending into the housing 77.

With the valve core 78 in the position indicated, the core 78 is provided with a longitudinal chamber 94 adjacent the end from which the hub 86 extends. The chamber 94 has a port 95 registering with the housing port 79a, and also has a port 96 registering with the housing port 84. The core chamber 94 has a third port 97 on that side of the core disposed outwardly in reference to the chamber 51 along which the housing 77 is disposed. This port 97 is centered on a horizontal transverse axis through the core 78. From the chamber 94, there opens another port 108 on that side of the core 78 removed 180 degrees from the port 79a and normally closed by the housing 77. Referring again to the valve housing 77, this housing 77 has a port 98 opening into the chamber 51, and then longitudinally spaced therefrom is a second port 99 also opening into the chamber 51, Figs. 1 and 3. The housing port 98 is located to permit registry of the port 97 therewith upon suitable turning of the valve core 78, while the under housing port 84 is closed off.

The valve core 78 is provided with a passageway 100 extending diagonally thereacross on a horizontally disposed axis, the line of this axis being at an acute angle herein shown as approximately 45 degrees, with the line of the transverse axis through the port 99. This passageway 100 has a port 101 in registry with the port 99, at the one end, and has a port 102 at the other end to be in registry with a passageway 103 extending diagonally outwardly through the housing 77. There is a port 104 opening through the top side of the valve core 78 from this diagonal passageway 100, and then there is a port 105 opening laterally from the inside portion of the core 78 at the end of a passageway 106 leading at right angles from the passageway 100. This port 105 is 180 degrees removed from the port 102, and upon 180 degrees rotation of the valve core 78, may be brought into registry with the passageway 103. Otherwise, the port 105 is closed off by the wall of the housing 77 as indicated in Fig. 1.

The port 104 is located longitudinally of the core 78 to be brought into registry with the under port 84 upon 180 degrees travel of the core 78.

In operation, when the motor 49 is running, a vacuum is produced initially within the chamber 50. From that chamber air is carried upwardly through the can 37 as above indicated and into the top pressure chamber 51, from which it may escape through the housing port 98, and out across the valve core 78 through the passageway 100 to discharge into the atmosphere through the housing passageway 103. The port 98 is closed. By reason of the vacuum produced in the chamber 50, air will be pulled from the chamber 13, through the wire mesh protector or dome 83, through the ferrule 81, the nipple 80, through the valve housing port 75, the valve port 79a, across the valve core passageway 94, and through the port 96, and the housing port 84 into the chamber 50.

The vacuum produced in the annular chamber 13, will cause air to be pulled upwardly from within the tank 10 through the hole 53, through the filtering medium 57, and into that chamber 13. Then the exhausting of the air from within the tank 10 will of course set up a partial vacuum at least within that tank, and this vacuum in turn

will cause air to flow in through the nipple 65, through the pipe 64, through the downturned portion of that pipe 66 into the cap 67, and then bubble up through the water from the opening 75 and also the opening 76 in the drum 68 therebelow so that the air has to travel through that water bath before it can then travel up through the opening 53. In this regard, the filtering medium 57 is primarily employed to eliminate and retain any particles of dust which may be carried in bubbles emanating from the surface of the water at the line 76. Thus it is to be seen that the device is operating as a vacuum producing machine to pull the air in through the nipple 65 and have that air washed at the lower end portion of the tank 10 and then be discharged out past the motor 40 into the atmosphere from the valve housing passageway 103.

Then at suitable intervals, depending upon the nature of the work to which the device is submitted, that is depending upon the degree of intake of dirt and dust into the tank 10 to be entrapped in the water therein, the lever 79 may be manipulated so as to discharge the dirt laden water. In this discharging action of the device, the handle 79, Fig. 6, is rocked from the solid line position around at least 180 degrees to the dotted line position. Since the lever 79 is normally spring returned, the handle 79 must be held in that dash line position while the evacuating process of the dirt is being carried out. Therefore it is to be seen that the valve core 78 has been rocked by the lever 79 at 180 degrees to effect a different flow of the air. In this rocked position of the valve core 78, the port 105 comes into registry with the passageway 103, the port 99 is closed, and the port 104 comes into registry with the port 85. Now this permits inflow of air from the passageway 103 and into the chamber 59 to the lower end of the can 37, and then upwardly through that can and into the top pressure chamber 51. The port 96 is closed off, and the port 97 comes into registry with the port 98. Also the port 103 comes into registry with the port 79a while the port 95 is closed off.

Therefore pressure generated in the chamber 51 causes air to flow therefrom and through the port 98, the port 97, across the valve core passageway 94, and down through the port 103 and out through the nipple 80, the ferrule 81, and into the chamber 13. Building up pressure in that chamber 13 causes the air to continue to flow onwardly through the filter medium 57, tending thereby somewhat to clean that medium by reverse flow and allow the flow to continue through the opening 53 down through the nipple 61 and into the tank 10 to generate pressure therewithin.

Pressure within the tank 10 will depress the level of the water 76 to cause it to flow upwardly and out the pipe 64. This forced flow of the water upwardly through the pipe 64 tends to agitate the water at the bottom of the tank 10 so that the water will carry the dirt along therewith. This outward flow of the water will continue until the level comes down to the opening of the cap 67 over the drum 68 at the slot 75 whereupon no further water will be lifted upwardly from the tank, although there will be water in the cap 67 and the pipe 66, all of which will drop when the water has reached that discharge level where the air tends to escape through the opening 75. Therefore when air begins to flow from the nipple 65, the handle 79 is released to allow it to return to its normal operating position, whereupon the entrapped water in the pipe 64 and the cap 75

67 will drop downwardly onto the floor 69 of the tank 10, the amount of water so entrapped being sufficient to maintain a level sufficiently high to cover the opening 75 in any event. This proportioning of the interior volumes of the pipe 64 and the cap 67 is made to be such as to serve as a safety factor whereby there will at all times be sufficient water within the tank 10 to insure air coming inwardly through the nipple 65 to be required to pass through the water.

Water will have to be replaced from time to time in the tank in order to maintain the desired level, and this is done by removing the dome 22 and the two pans 11 and 12 and pouring the water into the tank 10. A different method may be to draw water into the tank 10 through the nipple 65 in the ordinary vacuum producing action as above described. However this may lead to introducing too much water within the tank 10, and in such an instance, the water level should it reach a sufficient height within the tank 10, to float the ball 62, will carry that ball on up and close off the opening 53 whereby the water cannot be drawn up and eventually pass through the motor 40 to damage it. Of course the ball 62 will drop downwardly to open the opening 53 upon reduction of that water level.

While I have herein shown and described my invention in minor detail, it is obvious that structural variations may be employed such for example as above indicated in the exact construction of the valve in particular, and also in relation to the other structural details involving seals and the like, all without departing from the spirit of the invention, and I therefore do not desire to be limited to that precise form beyond the limitations which may be imposed by the following claims.

I claim:

40 1. A vacuum cleaning machine comprising in combination, a tank having three compartments, namely a pressure compartment, a vacuum compartment, and a major tank compartment adapted to hold water; vacuum producing means interposed between said vacuum and pressure compartments whereby said vacuum compartment is evacuated and content thereof discharged into said pressure compartment; single valve means for selectively interconnecting said vacuum and said pressure compartments with said tank compartment and, in reverse order, interconnecting said vacuum and said pressure compartments to the atmosphere, whereby said tank compartment may selectively be evacuated or 45 pressurized, a water and air discharge head in said tank compartment adjacent its floor; a conduit interconnecting said head with the atmosphere; and means carried by said head normally submerged in said water to retain a sufficient volume of water to water seal said conduit in said tank compartment following a tank compartment pressurization to that point to have air discharging from the conduit to the atmosphere, whereby subsequent air inflow through 50 the conduit from the atmosphere will be required to pass through an appreciable head of water.

55 2. A vacuum cleaning machine comprising in combination, a tank having three compartments, namely a pressure compartment, a vacuum compartment, and a major tank compartment; vacuum producing means interposed between said vacuum and pressure compartments whereby said vacuum compartment is evacuated and content thereof discharged into said pressure compartment; and single valve means for selectively in-

terconnecting said vacuum and said pressure chambers with said tank chamber and, in reverse order, interconnecting said vacuum and said pressure chambers to the atmosphere, whereby said tank chamber may selectively be evacuated or pressurized; a conduit in said tank compartment entering from the atmosphere; said tank being adapted to hold water therein; and a low water limit level determining head located to be submerged in part at least in said water; 10 said conduit being terminated interiorly of the tank compartment in said head; said head having vertically spaced openings and an offset chamber relative to and in communication with said conduit to carry a sufficient volume of water to cover the upper of said openings following an air flow through said conduit and release of said pressure.

3. A vacuum cleaning machine comprising in combination, a tank having three compartments, namely a pressure compartment, a vacuum compartment, and a major tank compartment; vacuum producing means interposed between said vacuum and pressure compartments whereby said vacuum compartment is evacuated and content thereof discharged into said pressure compartment; and single valve means for selectively interconnecting said vacuum and said pressure chambers with said tank chamber and in reverse order, interconnecting said vacuum and said pressure chambers to the atmosphere, whereby said tank chamber may selectively be evacuated or pressurized; a conduit in said tank compartment entering from the atmosphere; said tank being adapted to hold water therein; and a low water limit level determining head located to be submerged in part at least in said water; 15 said conduit being terminated interiorly of the tank compartment in said head; a filter chamber interposed between said valve means and said tank compartment; and float means sealing off entrance to said chamber upon said water reaching a predetermined high level.

4. A vacuum cleaning machine comprising in combination, a tank having three compartments, namely a pressure compartment, a vacuum compartment, and a major tank compartment; vacuum producing means interposed between said vacuum and pressure compartments whereby said vacuum compartment is evacuated and content thereof discharged into said pressure compartment; and single valve means for selectively interconnecting said vacuum and said pressure chambers with said tank chamber and in reverse order, interconnecting said vacuum and said pressure chambers to the atmosphere, whereby said tank chamber may selectively be evacuated or pressurized; and means yieldingly retaining said valve means in a normal condition for evacuation of said tank compartment.

5. A vacuum cleaning machine, comprising a tank adapted to hold water in a lower portion thereof and having a top opening; a pan having a flange formed to overlie the margin of said tank opening; a tank cover having a margin formed to overlie the marginal portion of said flange; sealing means interposed between said cover, flange and opening margins; a can positioned within said cover and said pan defining a chamber between it and said cover, sealed off from said pan; a motor driven air-flow means carried by said can to flow air into said chamber; said can having an opening outside of said chamber whereby air may be carried through said opening from said pan as a source for said flow;

10 said tank having a combined inlet and outlet orifice; a conduit within said tank for directing air inflowing from said orifice into said water; and valve means interposed between said chamber, said pan, and said tank for a normal air-flow from said tank into said pan, through said can and chamber, and out into the atmosphere, and for a tank cleaning air-flow from the atmosphere, into said pan, through said can and chamber, and into said tank to tend to evacuate it through said conduit.

6. A vacuum cleaning machine, comprising a tank adapted to hold water in a lower portion thereof and having a top opening; a pan having a flange formed to overlie the margin of said tank opening; a tank cover having a margin formed to overlie the marginal portion of said flange; sealing means interposed between said cover, flange and opening margins; a can positioned within said cover and said pan defining a chamber between it and said cover, sealed off from said pan; a motor driven air-flow means carried by said can to flow air into said chamber; said can having an opening outside of said chamber whereby air may be carried through said opening from said pan as a source for said flow; said tank having a combined inlet and outlet orifice; a conduit within said tank for directing air inflowing from said orifice into said water; and valve means interposed between said chamber, said pan, and said tank for a normal air-flow from said tank into said pan, through said can and chamber, and out into the atmosphere, and for a tank cleaning air-flow from the atmosphere, into said pan, through said can and chamber, and into said tank to tend to evacuate it through said conduit; and means at the lower, inner end of said conduit limiting discharge of said water therethrough.

7. A vacuum cleaning machine, comprising a tank adapted to hold water in a lower portion thereof and having a top opening; a pan having a flange formed to overlie the margin of said tank opening; a tank cover having a margin formed to overlie the marginal portion of said flange; sealing means interposed between said cover, flange and opening margins; a can positioned within said cover and said pan defining a chamber between it and said cover, sealed off from said pan; a motor driven air-flow means carried by said can to flow air into said chamber; said can having an opening outside of said chamber whereby air may be carried through said opening from said pan as a source for said flow; said tank having a combined inlet and outlet orifice; a conduit within said tank for directing air inflowing from said orifice into said water; and valve means interposed between said chamber, said pan, and said tank for a normal air-flow from said tank into said pan, through said can and chamber, and out into the atmosphere, and for a tank cleaning air-flow from the atmosphere, into said pan, through said can and chamber, and into said tank to tend to evacuate it through said conduit; a second pan spaced below said first pan and having a marginal flange outturned to overlie said tank opening margin and be within said sealing means; a filter chamber carried by said second pan having a tank opening and a second pan opening; and said valve means having its flow directed into said second pan and thence through said filter chamber.

8. A vacuum cleaning machine, comprising a tank adapted to hold water in a lower portion

thereof and having a top opening; a pan having a flange formed to overlie the margin of said tank opening; a tank cover having a margin formed to overlie the marginal portion of said flange; sealing means interposed between said cover, flange and opening margins; a can positioned within said cover and said pan defining a chamber between it and said cover, sealed off from said pan; a motor driven air-flow means carried by said can to flow air into said chamber; said can having an opening outside of said chamber whereby air may be carried through said opening from said pan as a source for said flow; said tank having a combined inlet and outlet orifice; a conduit within said tank for directing air inflowing from said orifice into said water; and valve means interposed between said chamber, said pan, and said tank for a normal air-flow from said tank into said pan, through said can and chamber, and out into the atmosphere, and for a tank cleaning air-flow from the atmosphere, into said pan, through said can and chamber, and into said tank to tend to evacuate it through said conduit; a second pan spaced below said first pan and having a marginal flange outturned to overlie said tank opening margin and be within said sealing means; a filter chamber carried by said second pan having a tank opening and a second pan opening; and said valve means having its flow directed into said second pan and thence through said filter chamber; and a float for closing off said filter chamber to tank opening upon a predetermined rise of water in said tank.

9. A vacuum cleaning machine comprising a tank adapted to hold water in a lower portion thereof and having a top opening; a tank cover sealably closing said tank, and provided with a pressure chamber; a pan extending across said tank forming a vacuum chamber under said cover; a vacuum producing unit having an intake from said vacuum chamber and a discharge into said pressure chamber; a conduit in said tank opening near the floor thereof by one end and externally of the tank by its other end; a valve interposed between said pressure chamber, said vacuum chamber, and said tank, and shiftable selectively to one of two positions, namely one position to open said pressure chamber to the atmosphere and interconnect said vacuum chamber with said tank for normal operation, and the second position of interconnecting said pressure chamber with said tank and opening said vacuum chamber to the atmosphere.

10. A vacuum cleaning machine comprising a tank adapted to hold water in a lower portion thereof and having a top opening; a tank cover sealably closing said tank, and provided with a pressure chamber; a pan extending across said tank forming a vacuum chamber under said cover; a vacuum producing unit having an intake from said vacuum chamber and a discharge into said pressure chamber; a conduit in said tank opening near the floor thereof by one end and externally of the tank by its other end; a valve interposed between said pressure chamber, said vacuum chamber, and said tank, and shiftable selectively to one of two positions, namely one position to open said pressure chamber to the atmosphere and interconnect said vacuum chamber with said tank for normal operation, and the second position of interconnecting said pressure chamber with said tank and opening said vacuum

chamber to the atmosphere; and a second pan disposed across said tank spaced below said first pan and sealably connecting by its peripheral edge portion with the tank; said machine having a passageway therewith leading from said valve and opening within said second pan; said second pan having an opening to said tank spaced from said passageway opening; and a filter medium over said second pan tank opening to catch dust and to return to said tank moisture tending to rise therefrom.

11. A vacuum cleaning machine comprising a tank adapted to hold water in a lower portion thereof and having a top opening; a tank cover sealably closing said tank, and provided with a pressure chamber; a pan extending across said tank forming a vacuum chamber under said cover; a vacuum producing unit having an intake from said vacuum chamber and a discharge into said pressure chamber; a conduit in said tank opening near the floor thereof by one end and externally of the tank by its other end; a valve interposed between said pressure chamber, said vacuum chamber, and said tank, and shiftable selectively to one of two positions, namely one position to open said pressure chamber to the atmosphere and interconnect said vacuum chamber with said tank for normal operation, and the second position of interconnecting said pressure chamber with said tank and opening said vacuum chamber to the atmosphere; and means normally returning and yieldingly holding said valve means in said one position.

12. A vacuum cleaning machine comprising a tank adapted to hold water in a lower portion thereof and having a top opening; a tank cover sealably closing said tank, and provided with a pressure chamber; a pan extending across said tank forming a vacuum chamber under said cover; a vacuum producing unit having an intake from said vacuum chamber and a discharge into said pressure chamber; a conduit in said tank opening near the floor thereof by one end and externally of the tank by its other end; a valve interposed between said pressure chamber, said vacuum chamber, and said tank, and shiftable selectively to one of two positions, namely one position to open said pressure chamber to the atmosphere and interconnect said vacuum chamber with said tank for normal operation, and the second position of interconnecting said pressure chamber with said tank and opening said vacuum chamber to the atmosphere; and means normally returning and yieldingly holding said valve means in said one position; said water tending to be forced out of said conduit upon said valve being in said second position; and a low water level limit head on the lower end of said conduit having an air leakage opening uncovered upon a predetermined lowering of water level in the tank while the lower end of said head remains submerged.
